 Buffalo Pressed Steel Company, Inc., Buffalo,
 N. Y.

Application July 20, 1937, Serial No. 154,624

15 Claims. (Cl. 181—54)

This invention relates to improvements in mufflers or silencers for use in connection with the silencing of the exhaust of internal combustion engines.

In my copending application Serial No. 137,686 filed April 19, 1937, I have disclosed a muffler of the reverse flow type in which is provided a device for doubling the pressure pulsations discharged into a muffler by an engine, and this is arranged with a muffler housing of relatively large diameter which provides a relatively large chamber extending about the inlet and discharge conduits and in which sound waves of low frequency are silenced after discharge of the same from the pulsation doubling device, and in this muffler the discharge conduit is provided with a high frequency acoustic train. In some installations it is more desirable to employ a muffler of smaller diameter and greater length, so that a large chamber extending about the inlet and discharge conduits for silencing low frequency sound waves cannot be provided.

One of the objects of this invention is to provide a muffler in which a pressure pulsation doubling device and a low frequency acoustic train may be incorporated in a muffler of relatively small diameter and in which a low frequency resonator chamber is provided for silencing low frequency sound waves.

Another object of this invention is to provide a muffler with a pulse doubling device at the inlet end thereof and having low and high frequency resonator chambers located in another portion of the muffler arranged rearwardly of the pulse doubling device.

It is also an object of this invention to provide a muffler of this kind with flow passages of improved construction for conducting the gases from the pulse doubling device to a discharge duct having resonator chambers associated therewith. Another object of the invention is to provide a muffler which is divided by means of a transverse partition into two parts, one of which contains the pulse doubling device and the other of which contains the resonator chambers.

Further objects of this invention will appear from the following description and claims.

In the accompanying drawings:

Fig. 1 is a longitudinal sectional central view of a muffler embodying this invention.

Figs. 2 and 3 are transverse sections thereof, on lines 2—2 and 3—3 respectively of Fig. 1, on an enlarged scale.

Figs. 4 and 5 are transverse sectional views of

mufflers respectively on lines 4—4, Fig. 6, and 5—5, Fig. 8.

Figs. 6, 7 and 8 are fragmentary longitudinal sectional views of mufflers provided with pressure pulse doubling devices of modified constructions.

Each of the several mufflers shown in this application is provided with an outer housing which may be of any suitable or desired construction, those shown being provided with an outer imperforate cylindrical shell A having at one end thereof an inlet head B provided with an outwardly extending flanged portion forming an inlet duct b to which the usual exhaust pipe from an engine may be attached. The other end 15 of the shell A, as shown in Fig. 1, may be closed by means of a head C having formed thereon a discharge duct c to which the usual tail pipe may be secured.

Referring to the muffler shown in Figs. 1 to 20 3, an inlet conduit 10 is provided, one end of which is suitably secured to the inlet head B to receive gases entering the muffler. For example, the conduit 10 may telescope within the inlet duct b and may be welded or otherwise secured thereto. The inlet duct is provided with an opening in the wall thereof, which may be in the form of a group of perforations 11 of any suitable type arranged adjacent to the gas receiving end of the conduit 10. These apertures or perforations 11 may, for example, be formed by providing slits in the conduit 10 which extend lengthwise thereof and the metal at one side of each slit may be pressed outwardly to form louvers 12, Fig. 2, which deflect gases discharged through the opening 11 in a more or less tangential direction with reference to the conduit 10.

In order to provide for the doubling of the pressure pulsations entering the muffler from the exhaust pipe of the engine, the conduit 10 terminates in a substantially closed chamber located beyond or rearwardly of the discharge openings or perforations 11, so that when a gas pressure pulsation enters the conduit 10, a portion of each pressure pulsation will pass outwardly through the opening or perforations 11 and another portion will be carried by its momentum past the perforations 11 and through the open end of the conduit 10 into the substantially closed chamber in which this portion of the pressure pulsation is reversed so that it flows back in the conduit 10 to the opening or perforations 11 and discharges through the same after and out of phase with that portion of the pres- 55

sure pulsation which has already passed through the perforations 11.

Any suitable means may be employed for constructing a substantially closed chamber of this type, and in the construction illustrated, I provide an intermediate shell 15 which is supported from the conduit 10 by means of a transverse wall or baffle 16. The rear end of the intermediate shell 15 may be closed in any suitable or desired manner, for example, by means of a cap or baffle 17, so that a substantially closed chamber 18 is formed in an enclosure comprising the baffle 16, the cap 17 and the portion of the intermediate shell 15 connecting this baffle and cap. An enclosure formed in any other manner may, of course, be employed if desired. The enclosure may form a chamber which is entirely closed except for the entrance provided by the inner conduit 10, or if desired, to reduce natural resonance phenomena of this enclosure, a few relatively small apertures 19 may be provided, for example, in the intermediate shell 15 which should be of small enough size and number so that only a relatively small part of the gases entering the closed chamber 18 will escape through the apertures 19.

The intermediate shell 15 in the particular construction shown in Fig. 1, may, if desired, or if necessary to stop shell noises resulting from the impinging of the gases discharged from the perforations 11 on the outer shell A, extend forwardly from the baffle 16 toward the inlet head B of the muffler about the opening or perforations 11 of the conduit 10 and preferably the forward end of the intermediate shell 15 is secured to the housing of the muffler by means of a shouldered ring 20, that shown having an inner shoulder welded or otherwise secured to the intermediate shell 15 and an outer shoulder secured to the outer shell A. The portion of the intermediate shell between the baffle 16 and the ring 20 is provided with openings of any suitable form, such for example as the louvered apertures 21 clearly shown in Fig. 2. Consequently, gases discharged through the apertures 11 of the inner conduit will pass through the apertures 21 of the intermediate shell into an annular space 22 between the intermediate shell 15 and the outer shell A.

The inner conduit 10 may terminate at the entrance to the closed chamber 18, or if desired, it may extend into the same and the portion of the conduit within the closed chamber 18 may be provided lengthwise thereof with a series of openings or perforations 24. This construction permits the gas to expand more uniformly from the conduit into the closed chamber 18 and reduces the turbulence which results from gas breaking directly out of the relatively small conduit 10 into the relatively large pulse doubling chamber 18. This portion of the conduit 10 may, however, be omitted, if desired.

The gases after leaving the pulse doubling device pass rearwardly in the annular space 22. If desired to provide a support for the rear end of the intermediate shell 15, this may be done by providing the cap member 17 with an outwardly extending flange portion 25 terminating in a longitudinally extending flange 26 which may engage or be secured to the outer shell A. The outwardly extending flange portion 25 is provided with openings, such for example as arcuate slots 27, see particularly Fig. 3, through which the gases may pass from the annular space 22 into a chamber 30 formed between the cap or head

17 of the rear end of the pulse doubling chamber 18 and a transversely extending baffle 31, that shown being of substantially semi-spherical form and being provided with a central flanged aperture 32 to which a discharge conduit 33 may be secured. The other end of this discharge conduit terminates within the duct c of the head C. It will be noted that the partition or baffle 31 divides the muffler housing into two parts, one of which contains the pulse doubling device and the other part of the housing may contain other flow equalizing or sound wave cancelling means.

The discharge conduit 33 is preferably provided with groups of perforations or openings 34, 35, 36 and 37 which may be of any suitable form, for example, similar to the louvered perforations 11 in the conduit 10. One or more of these groups of perforations are preferably enclosed by means of a suitable shell extending about the conduit 33 to form therewith high frequency resonator chambers. In the construction illustrated, an intermediate shell 40 is provided for this purpose having its end portions 41 extending inwardly into engagement with the discharge conduit 33 and the middle portion of the intermediate shell 40 also has an inwardly extending portion 42 which contacts with the discharge conduit between the groups of perforations 36 and 37. This shell 40 may, of course, be of any suitable or desired construction to form an enclosure for a portion of the discharge conduit 33 and may either be made of a single tubular shell as described, or of any other construction, such for example as the longitudinally split multi-piece shell described in the MacKenzie, Haas and Starkweather application for patent, Serial No. 89,606 filed July 8, 1936. The intermediate shell shown forms with the discharge conduit a high frequency acoustic train comprising two high frequency resonator chambers 44 and 45.

The conduit 33 and intermediate shell 40 are arranged within a chamber 47 within the muffler housing and by providing the high frequency resonator chambers adjacent to the discharge end of the conduit 33, the groups of apertures 34 and 35 will establish communication between the interior of the discharge conduit 33 and the chamber 47, a portion of which extends into the space between the intermediate shell 40 and the outer shell A. This chamber, therefore, forms a low frequency resonator chamber by means of which low frequency sounds are silenced and this chamber also helps to equalize the flow of gases discharged from the muffler in that the peaks of pressure waves may pass through the apertures 34 and 35 into the chamber 47 and then return through these apertures during low pressure intervals in the conduit. The arrangement shown in Fig. 1 also has the advantage that the gases and sound waves are subjected to the action of the high frequency acoustic train after they have been subjected to the action of the pulse doubling device and the low frequency resonator chamber, which results in the most effective action of the high frequency chambers.

The action of the muffler thus far described can be under certain conditions improved by introducing a resistance to the flow of gas in the discharge conduit 33. By way of example, I have illustrated in the conduit between the perforations 34 and 35 an annular restricting member 48, having an outer annular flange secured to the inner surface of the conduit 33 and having a sleeve portion of reduced diameter. Any other

type of restriction may, of course, be employed in place of the one shown. This restriction tends to cause the flow of gases in the conduit 33 to become more uniform. By locating the restriction 48 between the groups of perforations 34 and 35, a by-passing of a portion of the gases through the perforations 34 into the chamber 47 and then back into the conduit 33 through the perforations 35 results and gases and sound waves taking this by-pass or circuitous route will, of course, enter the conduit 33 out of phase with the portions of the gas pressure and sound waves which have passed directly through the restriction 48. This arrangement of the restriction in the conduit, consequently, equalizes the flow of gases without any material increase in the back pressure of the muffler.

In the operation of the muffler which has been described, an intermittent flow of gas is discharged from the engine into the inlet conduit 10, this flow consisting of a series of pulses of gas with high velocities and probably possessing a peaked wave form. The number of such pressure pulses entering the muffler depends upon the engine speed and the wave form of the pressure pulses varies with different engines, depending upon such factors as piston displacement, operation of exhaust valves, and the like. When a series of these rather violent pressure pulses passes through the exhaust pipe and into a muffler, it excites masses of gases in the exhaust system into vibration and a definite prolonged after-effect probably exists after a series of such pulses has passed. The muffler shown in Figs. 1 to 3 smooths out this intermittent flow into an approximately even or steady one before any of the gas is discharged to the atmosphere. This is due, in the first place, to dividing the pressure peaks or pulses into two or more parts, the first part of each pressure pulse passing outwardly through the perforations 11 while the pressure pulse is moving lengthwise of the conduit 10. The remainder of the pressure pulse passes into the pulse doubling chamber 18 and most of it is then returned to the conduit 10 and discharged through the perforations 11 after the first part of the pressure pulse has passed through these perforations. Portions of the second part of the pressure pulse will also pass through the apertures 19 in the intermediate shell 15 and this part of the pressure pulse will also be somewhat out of phase with the two parts of the pulse which pass through the apertures 11. The separate parts of the pressure pulse which will, of course, be of greatly reduced intensity as compared with the pulse originally received by the muffler, will then pass successively along the annular passage 22 and through the slots 27 into the chamber 30 from which they enter into the discharge conduit 33. In this conduit, the peaks of the remaining pressure waves, as well as sound waves, pass out through the apertures 34 and 35 into the relatively large chamber 47 which acts not only as a low frequency resonator chamber, but also as an expansion or equalizing chamber. The restriction or diffuser 48 also serves to equalize the flow of gases through the conduit 33 by slightly holding back the peaks of the waves and by forcing a considerable portion of the gas to by-pass the restriction 48 by passing out of the apertures 34 and again entering the conduit 33 through the apertures 35. Consequently, by the time the gases and sound waves reach the portion of the conduit 33 enclosed in the intermediate shell 40, a relatively uniform flow of gas has been pro-

duced so that the high frequency acoustic train formed by the resonator chambers 44 and 45 acts very effectively upon the gases and remaining sound waves passing through the conduit 33.

In Figs. 6 to 8, I have shown the inlet portions 5 only of mufflers of slightly modified construction. The muffler shown in Fig. 6, for example, differs from the muffler shown in Figs. 1 to 3 only in that the conduit 50 terminates at the baffle 51 which forms a part of the enclosure of the pulse 10 doubling chamber 52. Otherwise the structure shown is similar to that shown in Fig. 1.

In Fig. 7 another slightly modified form of muffler is shown, in which a short inlet conduit 55 is provided, as shown in Fig. 6, and in which an 15 intermediate shell 56 is provided which terminates at a baffle 57 which forms a part of the enclosure 20 of the pulse doubling chamber 58. In this construction, the intermediate shell 56 does not extend around openings or apertures 59 of the inlet 25 conduit 55. A muffler of this kind may be used in connection with engines in which the exhaust is such that no objectionable shell noises are produced, if the gases are discharged from the inlet conduit directly against the outer shell A of the 25 muffler.

The muffler shown in Fig. 8 is similar to the one shown in Fig. 1, except that in this case the intermediate shell 60 is short and does not extend over the perforations 61 of the inlet conduit 62 30 of the muffler. This construction differs from the one shown in Fig. 7 in that the inlet conduit has a part or extension 63 which enters into the pulse doubling chamber 64 and is provided with 35 perforations 65 similar to the perforations 24 described in Fig. 1.

It will, of course, be understood that the various constructions illustrated are merely examples of mufflers which embody my invention and it will be obvious that my invention may be embodied in other structures than those herein illustrated, since it is not intended to limit this invention to the constructions shown.

I claim as my invention:

1. A muffler including a housing with an inlet 45 at one end thereof and an outlet at the opposite end, an inlet conduit and a discharge conduit connected respectively with said inlet and outlet and extending toward each other in said housing, said inlet conduit having apertures for the discharge of gases, an enclosure forming a substantially closed chamber in which the open end of said inlet conduit terminates and which is arranged rearwardly beyond said apertures, said closure being spaced from said housing to form 50 a passage extending lengthwise of said housing for gases discharged through said apertures, and means located rearwardly of said enclosure for conducting gases discharged from said passage into said discharge conduit. 55

2. A muffler including a housing with an inlet at one end thereof and an outlet at the opposite end, an inlet conduit connected at one end to said inlet and having its other end open and having an opening in a side thereof, an enclosure 65 arranged rearwardly beyond said opening and forming a substantially closed chamber in which said open end terminates and in which gas pressure pulses are reversed and returned to said conduit for discharge through said opening, means 70 for conducting gases discharged through said opening rearwardly of said housing beyond said enclosure, an acoustic filter through which said gases pass on their way to said outlet. 75

3. A muffler including a housing with an inlet

- 5 at one end thereof and an outlet at the opposite end, an inlet conduit connected at one end to said inlet and having its other end open and having an opening in a side thereof, an enclosure forming a substantially closed chamber in which said open end terminates and in which gas pressure pulses are reversed and returned to said conduit for discharge through said opening, means for conducting gases discharged through
- 10 5 said opening rearwardly of said housing beyond said enclosure, a transversely extending baffle in said housing beyond the rear end of said enclosure, a discharge conduit connecting said baffle and said outlet and having a perforate portion, and an intermediate shell enclosing said perforate portion of said discharge conduit and forming therewith a high frequency resonator chamber.

4. A muffler including a housing with an inlet 20 at one end thereof and an outlet at the opposite end, an inlet conduit connected at one end to said inlet and having its other end open and having an opening in a side thereof, an enclosure forming a substantially closed chamber in which 25 said open end terminates and in which gas pressure pulses are reversed and returned to said conduit for discharge through said opening, means for conducting gases discharged through said opening rearwardly of said housing beyond 30 said enclosure, a discharge conduit arranged in said housing and receiving gases at the rear of said chamber and having perforate portions, and an intermediate shell enclosing one of said perforate portions and forming therewith a high 35 frequency resonator chamber, said other perforate portion of said discharge conduit establishing communication between the interior of said conduit and a space between said housing and the exterior of said conduit and forming a low 40 frequency resonator chamber, said discharge conduit connecting with said outlet.

5. A muffler including a housing with an inlet at one end thereof and an outlet at the opposite end, an inlet conduit connected at one end to said inlet and having its other end open and having an opening in a side thereof, an enclosure forming a substantially closed chamber in which said open end terminates and in which gas pressure pulses are reversed and returned to said conduit for discharge through said opening, means for conducting gases discharged through said opening rearwardly of said housing beyond said enclosure, a transversely extending baffle in said housing beyond the rear end of said enclosure, a discharge conduit arranged in said housing and having groups of perforations arranged at intervals lengthwise of said discharge conduit, and an intermediate shell arranged in spaced relation to said conduit and housing and enclosing a group of perforations arranged near the rear end of said discharge conduit, another group of perforations arranged in advance of said intermediate shell establishing communication between the interior of said discharge conduit 55 and a chamber formed between said housing and said intermediate shell and conduit and forming a low frequency resonator chamber.

6. A muffler including an outer housing having an inlet at one end thereof and an outlet 70 at the other end thereof, an inlet conduit connected at one end with said inlet and having an opening in the wall thereof, an enclosure in which the other end of said inlet conduit terminates and which forms a substantially closed pressure pulse doubling chamber, means for con-

ducting gas discharged from said opening rearwardly beyond the rear end of said enclosure, a discharge conduit into which gases pass beyond the rear of said enclosure and having a group of perforations, and a shell arranged about said 5 conduit and enclosing said group of perforations to form a high frequency resonator chamber, said shell forming with said outer housing a low frequency resonator chamber, said conduit having an opening through which gases and sound 10 waves may pass into said low frequency resonator chamber.

7. A muffler including an outer housing having an inlet at one end thereof and an outlet at the other end thereof, a transverse baffle in said 15 housing dividing the interior of said housing into two parts, an enclosure arranged in the one of said parts located at the inlet end of said muffler and spaced from said housing and from said baffle, an inlet conduit connecting said 20 inlet with said enclosure and having an opening in the wall thereof arranged between said inlet and said enclosure, a perforate discharge conduit connecting said baffle and said outlet and extending lengthwise of the other part of 25 said housing, and sound attenuating means arranged in said other part.

8. A muffler including an outer housing having an inlet at one end thereof and an outlet at the other end thereof, a transverse baffle in said 30 housing dividing the interior of said housing into two parts, an enclosure arranged in the one of said parts located at the inlet end of said muffler and spaced from said housing and from said baffle, an inlet conduit connecting said 35 inlet with said enclosure and having an opening in the wall thereof arranged between said inlet and said enclosure, and a perforate discharge conduit connecting said baffle and said outlet and forming with said other 40 part of said muffler housing a low frequency resonator chamber.

9. A muffler including an outer housing having an inlet at one end thereof and an outlet 45 at the other end thereof, a transverse baffle in said housing dividing the interior of said housing into two parts, an enclosure arranged in the one of said parts located at the inlet end of said muffler and spaced from said housing and from said baffle, an inlet conduit connecting said inlet with 50 said enclosure and having an opening in the wall thereof arranged between said inlet and said enclosure, a perforate discharge conduit connecting said baffle and said outlet and extending lengthwise of the other part of said housing, and a shell arranged in said other part and enclosing a 55 perforate portion of said discharge conduit and dividing said other part into high frequency and low frequency resonator chambers.

10. A muffler including an outer housing having an inlet at one end thereof and an outlet at the other end thereof, a transverse baffle in said housing dividing the interior of said housing into two parts, an enclosure arranged in the one 65 of said parts located at the inlet end of said muffler and spaced from said housing and from said baffle, an inlet conduit connecting said inlet with said enclosure and having an opening in the wall thereof arranged between said inlet and said 70 enclosure, a perforate discharge conduit connecting said baffle and said outlet and extending lengthwise of the other part of said housing, sound attenuating means arranged in said other 75 part, and a restriction in said discharge conduit

for equalizing the discharge of gases from said discharge conduit.

closed chamber in which the open end of said inlet conduit terminates, said enclosure being spaced from said housing to form a passage for gases extending lengthwise of said housing, apertures in said enclosure to reduce natural resonance phenomena therein and opening into the space between said enclosure and said housing, and means beyond the rear end of said enclosure for conducting gases to said discharge conduit.

11. A muffler including an outer housing having an inlet at one end thereof and an outlet at the other end thereof, a transverse baffle in said housing dividing the interior of said housing into two parts, an enclosure arranged in the one of said parts located at the inlet end of said muffler and spaced from said housing and from said baffle, an inlet conduit connecting said inlet with said enclosure and having an opening in the wall thereof arranged between said inlet and said enclosure, a discharge conduit connecting said baffle and said outlet and extending lengthwise of the other part of said housing and having groups of perforations arranged lengthwise thereof, and a restriction in said discharge conduit arranged between groups of perforations.

12. A muffler including an outer housing having an inlet at one end thereof and an outlet at the other end thereof, a transverse baffle in said housing dividing the interior of said housing into two parts, an enclosure arranged in the one of said parts located at the inlet end of said muffler and spaced from said housing and from said baffle, an inlet conduit connecting said inlet with said enclosure and having an opening in the wall thereof arranged between said inlet and said enclosure, a discharge conduit connecting said baffle and said outlet and extending lengthwise of the other part of said housing and having groups of perforations arranged lengthwise thereof, a restriction in said discharge conduit arranged between groups of perforations, and an intermediate shell enclosing another group of perforations to form a high frequency resonator chamber.

13. A muffler including a housing with an inlet at one end thereof and an outlet at the opposite end, an inlet conduit and a discharge conduit connected respectively with said inlet and outlet and extending toward each other in said housing, said inlet conduit having apertures for the discharge of gases, an enclosure forming a substantially closed chamber in which the open end of said inlet conduit terminates, said enclosure being spaced from said housing to form a passage for gases extending lengthwise of said housing, said enclosure including a shell having a portion thereof extending about said apertures of said inlet conduit to reduce shell noises and having an opening communicating with said passage, and means for conducting gases from the rear end of said passage to said discharge conduit.

14. A muffler including a housing with an inlet at one end and an outlet at the opposite end, an inlet conduit and a discharge conduit connected respectively with said inlet and outlet and extending toward each other in said housing, said inlet conduit having apertures for the discharge of gases, an enclosure forming a substantially closed chamber in which the open end of said inlet conduit terminates, said enclosure being spaced from said housing to form a passage for gases extending lengthwise of said housing, said enclosure including a shell having a portion thereof extending about said apertures of said inlet conduit to reduce shell noises and having an opening communicating with said passage, and means for conducting gases from the rear end of said passage to said discharge conduit.

15. A muffler including a housing with an inlet at one end thereof and an outlet at the opposite end, an inlet conduit and a discharge conduit connected respectively with said inlet and outlet and extending toward each other in said housing, an enclosure forming a substantially closed chamber in which the open end of said inlet conduit terminates, said inlet conduit having a discharge opening in the wall thereof located in advance of said chamber and through which some gases pass without entering said chamber and through which other gases pass which have re-entered said inlet conduit from said chamber, and means for conducting gases from said opening to the rear of said chamber to said discharge conduit.

LUTHER GRANT HECTOR.
